[57] CLAIM

The ornamental design for a head-mount type image display device, as shown and described.

DESCRIPTION

FIG. 1 is a front view of a head-mount type image display device showing my new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof;

FIG. 7 is a perspective view from front direction thereof;

FIG. 8 is a perspective view from rear direction thereof; and,

FIG. 9 is a perspective view where a terminal controller is connected to an article.

The terminal controller has not been repeated in FIGS. 1-8 for clarity.
